UNITED STATES PATENT OFFICE.

CHARLES A. ROLFE, OF REDLANDS, CALIFORNIA.

INFORMATION PLATE.

Application filed October 10, 1927. Serial No. 225,353.

This invention has to do generally with information plates, and is more particularly concerned with means for displaying pertinent information on the fronts of telephone transmitters. For instance, such information may be in the nature of the exchange number of the equipped phone and emergency call numbers.

It may be considered as the general object 10 of the invention to provide an information plate of this type which may be applied to and removed from the transmitter with ease and without mutilating the instrument, and yet so fashioned that it may be held stationarily in predetermined position on the transmitter without necessitating the use of independent attachment elements.

With printed information on the plate, it is obviously essential to maintain the plate stationarily in a given position in order that said information may be presented properly at all times. The information plate is mounted on the mouthpiece of the transmitter at a point adjacent the face of the transmitter body, but it will be apparent that should the plate be rotatable upon the mouthpiece, it would be capable of being inadvertently rotated out of proper position. Furthermore, in order that the plate may not project beyond the edge of the transmitter body and thereby interfere with easy operation of the associated receiver and its hook, the plate is necessarily confined to a shape approximating that of the face plate of the transmitter. It follows that the central mounting of the plate on the mouthpiece leaves said plate in balance no matter to what position it is rotated, and therefore, with the plate liable to be rotated out of position, there would be every likelihood that the telephone user would have to rotate the plate back to proper position each time he had occasion to refer to it. Of course, this could be overcome by properly over-weighting the plate at one side, but such a provision necessarily would add to the expense of the installation and would be generally undesirable.

From the above it will be apparent that in order to be thoroughly satisfactory, means must be provided to hold the plate against movement from a predetermined position, and yet the means must be such as will call for no special attachment members and which will in no way mutilate or deface the instrument.

I have accomplished the above by so fasten-

ing the plate that a portion thereof is adapted to extend and be clamped between the body of the transmitter and the annular shoulder provided on every standard mouthpiece for limiting the movement of the mouthpiece toward the body. To apply the plate it is only necessary to unscrew the mouthpiece from the transmitter body, slip the information plate over the threaded extremity of the mouthpiece, and then screw the mouthpiece back into the transmitter body until the plate is clamped tightly between the aforementioned shoulder and the transmitter body, care being taken that the plate be rotated to a position properly presenting its information before the mouthpiece is threaded fully home.

Other objects and characteristics of the information will be made apparent in the following detailed description, reference being had to the accompanying drawings, in which:

Fig. 1 is a detached front elevation of a transmitter body showing an information plate applied thereto, the mouthpiece being broken away to expose a portion of the plate, where it lies therebeneath;

Fig. 2 is a section on line 2—2 of Fig. 1;

Fig. 3 is a view generally similar to Fig. 1, but showing a modified type of information plate; and

Fig. 4 is a section taken about on broken line 4—4 of Fig. 3.

I have indicated somewhat conventionally a transmitter body 10 including shell 11 and face plate 12, the latter having a centrally pressed out portion 12 which is centrally apertured and internally threaded as at 14. There is thus presented an annular shoulder 15 spaced horizontally from the major portion of face plate 12. As is usual, mouthpiece 16 is of reduced diameter at one extremity 17, said extremity having threads 18 adapted to engage threads 14 for holding the mouthpiece and transmitter body detachably in assembly. Adjacent extremity 17 there is presented on mouthpiece 16 an annular shoulder 19 which faces body 10 and which is normally adapted to engage shoulder 15 when the mouthpiece is screwed fully home.

Information plate 20 is preferably, though not necessarily, in the form of a thin cardboard or metal disk which is centrally apertured at 21 to take mouthpiece 16. The information displayed on this plate may be of any desired character; for instance, there may be an outlined number panel 22, having thereon the particular number 23 of the equipped

telephone. There may also be printed on the plate certain emergency call numbers, such as that indicated at 24, or any other pertinent information.

5 It will be evident, in order that plate 20 remain constantly in a position to present its information properly to the eye of the telephone user, that said plate must be held against rotation about the mouthpiece. It 10 is also desirable that the plate be held from movement longitudinally along the mouthpiece and from tilting movement which might occur even though the plate fitted the mouthpiece comparatively snugly at a point adjacent body 10, due to the fact that the outer edges of the plate are necessarily spaced horizontally from the forward face of the transmitter body.

I accomplish this releasable holding by so 20 fashioning plate 20 that a portion 25 thereof is adapted to be taken between shoulders 15 and 19. In order to insure that plate 20 be centered with the transmitter body and mouthpiece when said plate is installed, aperture 20 is preferably of a diameter just to take reduced portion 17. A further advantage results from this provision in that it insures an approximately complete annular bearing of shoulder 19 on the plate portion 25, there 30 then being less likelihood of the mouthpiece being loosened by vibrations and the like.

In applying the information plate, it is merely necessary to unscrew mouthpiece 16 from body 10, slip plate 20 over extremity 17, 35 and then screw the mouthpiece home, care being taken that the information plate be rotated to proper position before the mouthpiece had been screwed far enough in to exert a clamping action on said plate. It will be 40 evident that when the mouthpiece is screwed fully home it clamps plate 20 against shoulder 15 to hold the plate against rotation and movement longitudinally of the body axis. Furthermore, the plate 20 is held against tiltable movement toward and away from body 45 10 in spite of the fact that said plate is horizontally spaced from the main plane of the transmitter front.

In Figs. 3 and 4 I have illustrated a modified embodiment of the invention wherein there is provided a separable number panel 22^a on information plate 20^a. This feature makes it possible to print any quantity of standard information plates and then provide 55 individual number panels for the individual telephones to be equipped. The economic advantage of this feature is self-evident.

While panels 22^a may be held to the plate in any desired manner, a preferred method 60 of securing is illustrated. Plate 22 is provided with spaced, parallel slits 26 through which the opposite ends 27 of panel 22^a are adapted to extend, the panel preferably being made of paper or thin card-board, and plate 20^a being of such material that it has

sufficient resilience to exert a slight binding pressure on the panel and thus hold it approximately in correct position. However, in order that the insertion of panels 22^a may be accomplished with ease, slits 26 are somewhat 70 longer than the panel is wide. Consequently there is some tendency for the panel to shift with respect to the face plate. In order to prevent such shifting, as well as any other movement of the panel with respect to the plate, I so locate slits 26 and position panel 22^a on plate 20^a that, when said plate is mounted on the transmitter in the manner illustrated in Fig. 4 (which is equivalent to the mounting of plate 20 in Fig. 2), a portion 80 25^a of said panel extends between shoulder 19 and said plate, or, in effect, between shoulders 19 and 15. Consequently, when mouthpiece 16 is threaded home, panel 22^a is held against movement with respect to plate 20^a and said 85 plate is held against movement with respect to the transmitter.

Should the number of the equipped phone be changed, it is evident that it is a matter of ease to remove the plate from the transmitter 90 and replace panel 22^a with a properly numbered panel, the plate then being remounted in the manner set forth above to retain both the plate and panel in predetermined position.

95 It will be understood the drawings and description are to be considered merely as illustrative of and not restrictive on the broader claims appended hereto, for various changes in design, structure and arrangement may 100 be made without departing from the spirit and scope of said claims.

I claim:

1. In combination with a telephone transmitter which includes a body member and a mouth piece having an extremity threadably connected to the body member, there being an external annular shoulder on the mouth piece adjacent said extremity and facing the body member, a detachable information plate 110 having an opening through which said extremity extends, a number panel mounted on the information plate for movement with respect thereto when the plate is detached from the transmitter, a portion of said plate and a portion of said panel extending and being clamped between said shoulder and the body member by virtue of screw-thread movement of the mouth piece toward the body member, all in a manner whereby the panel is held 115 against movement with respect to the plate and the plate is held against movement with respect to the body member.

120 2. In combination with a telephone transmitter which includes a body member and a mouthpiece having an extremity threadably connected to the body member, there being an external annular shoulder on the mouth piece adjacent said extremity and facing the body member, a detachable information plate hav- 125 130

ing an opening through which said extremity extends, said plate also having a pair of substantially parallel, spaced slits extending therethrough, an elongated number panel in 5 facial engagement with the plate at one side thereof and having its opposite ends extending through and beyond said slits to the other side of the plate, the reception of said ends in 10 the slits mounting the panel on the plate for longitudinal movement with respect thereto when the plate is detached from the transmitter, a portion of the plate and an edge of said

panel extending and being clamped between said shoulder and the body member by virtue of screw-thread movement of the mouth piece 15 toward the body member, all in a manner whereby the panel is held against movement with respect to the plate and the plate is held against movement with respect to the body member. 20

In witness that I claim the foregoing I have hereunto subscribed my name this 19th day of September, 1927.

CHARLES A. ROLFE.
